UNITED STATES PATENT OFFICE.

GEORGE D. FULL, OF WAUKEGAN, ILLINOIS.

LOCK.

Application filed September 4, 1924. Serial No. 735,785.

To all whom it may concern:

Be it known that I, GEORGE D. FULL, a citizen of the United States, residing at Waukegan, in the county of Lake and State of Illinois, have invented certain new and useful Improvements in Locks, of which the following is a specification.

This invention relates to improvements in a type of combination or permutation locks for swinging or hinged doors, particularly those of buildings, but not restricted thereto in its use, and consists in the novel construction, arrangement and combination of the various parts thereof, as will be hereinafter more fully set forth and specifically claimed.

An object of the invention is, to provide a lock of the above mentioned general character which shall be comparatively simple in construction, with its parts so made, arranged and co-operating with one another and with the door knobs that it may be manipulated to throw it into a locked or unlocked position, and also, that it may be used as an ordinary latch.

Another object is to provide means in a combination lock for readily changing the permutation or combination thereof whenever deemed advisable.

Other objects and advantages of the invention will be disclosed in the following description and explanation, which will be more readily understood when read in conjunction with the accompanying drawings, in which an embodiment of the invention is illustrated, it being understood that changes and modifications may be resorted to without a departure from the spirit of the invention so long as they come within the scope of the appended claims forming a part hereof.

In the drawings,—

Fig. 1 is a perspective view of a portion of the door frame and door of a building or other structure and showing the door equipped with a lock embodying my improvements and illustrating the lock as being mounted on the face or outside surface of the door.

Fig. 2 is a greatly enlarged view partly in elevation and partly in section of parts of the door frame and door showing the lock casing seated in a recess or mortise in the door with the front part of said casing removed.

Fig. 3 is a vertical sectional view taken

on line 3—3 of Fig. 2 as indicated by the arrows, showing the parts in the positions they will occupy with respect to the knobs of the door.

Fig. 4 is a horizontal sectional view taken on line 4—4 of Fig. 2 as indicated by the arrows.

Fig. 5 is a plan sectional view taken on line 5—5 of Fig. 3 looking in the direction indicated by the arrows.

Fig. 6 is a rear view partly in section and partly in elevation of a fragment of the rear wall of the lock casing and a part of the knob spindle located on the rear surface of the door or the inner surface thereof.

Fig. 7 is a detached face view of an arm or element used in co-operation with the inner knob spindle 28 for retracting the latch, and

Fig. 8 is a face view of the outermost tumbler of the device.

Corresponding numerals of reference refer to like parts throughout the different views of the drawings.

The reference numeral 10 designates a portion of one side of a door frame which is equipped with a recess or socket 11, in its edge adjacent the door 12 for the reception of the latch or locking bolt 13 of the lock when the same is projected for either locking or latching the door. Located in a mortise 14 of any suitable size and shape with which the door 12 is provided in its portion adjacent the frame 10 is the lock casing 15, which is by preference rectangular in shape as shown and has on the inner surface of its rear wall 16 near its top and bottom a pair of apertured or socketed bosses 17, which apertures are by preference screw-threaded to engage screws not shown, employed for securing the front wall or face plate 18 of the lock casing in position, which latter plate will rest on the front ends of the bosses or studs 17 as is clearly shown in Fig. 3 of the drawings. The rear plate 16 is provided about midway between its top and bottom with a circular opening 19 for the reception and operation of the inner end of the knob spindle designated as a whole by

the numeral 20 for the front knob 21 of the door or that knob which is located outwardly of the door. This opening 19 is also employed to receive and hold one end of a sleeve 22 which extends from the rear wall 16 of the casing to the front wall 18 thereof and is fitted within an opening 23 therein,

see Fig. 5, in any well known way so as to permit of rotation of said sleeve. The plate 16 of the lock casing is provided just above its opening 19 with a segmental slot 24 and 5 just below said opening with another similar slot 25 for the reception and operation of a pair of projections 26 arranged in spaced relation to one another on the inner face of the hollow head 27 of the knob spindle 28 for the rear knob 29 or that one located on the inner surface of the door.

These projections 26 are employed for the purpose of engaging a pair of openings 29^a in an arm 30, which arm is pivotally connected near its outer end to the rear surface of one of the prongs 31 of the latch or locking bolt 13, which as is clearly shown in Fig. 2 of the drawings, is substantially U-shaped when viewed in front elevation and has said 15 prongs so spaced and located as to slidably rest against the studs 36 on opposite sides thereof and also so arranged as to stride the tumblers and spacing members therefor, which will be hereinafter referred to without interference therewith. The arm 30, as 20 is clearly shown in Fig. 7, is provided inwardly of its pivot 32 with a disk-like enlargement 33 which has a central opening for the reception of the sleeve 22 and is provided with the openings 29^a at diametrically 25 opposite points with respect to said central opening for the reception of the projection 26 carried by the head or enlargement 27 of the knob spindle 28 to which the knob 29 30 may be detachably secured by means of a screw 34 seated in a portion of said knob and engaging said spindle. The arm 30 is also provided in its disk portion 33 with a 35 recess 35 for the purpose to be presently explained.

Uniting the rear and front plates 16 and 18 respectively of the locking casing are a pair of studs 36 which are diametrically spaced with respect to the sleeve 22 and are 40 employed for the purpose of holding a pair of washers and spacing rings interposed between certain elements of the locking mechanism against rotary movement. The casing 45 is provided on the inner surface of its inner side wall with a pair of spaced studs 37 for the support of a pair of spiral springs 38 each of which surrounds at one of its ends one of said studs and rests at its other end against the inner end of one of the prongs 31 of the latch or locking bolt 50 which is designated as a whole by the reference numeral 13 as before indicated. This latch or locking bolt is provided midway between its prongs 31 with a guide-way 39 for a plunger 40 which has its inner portion reduced as at 41 for the purpose of engaging certain recesses in the tumblers and spacing rings as will be hereinafter explained. The plunger 40 has on its front surface a 55 projection or pin 42 for co-operation with a

slot 43 in a cam plate designated as a whole by the numeral 44, the construction of which is clearly shown in Fig. 2 of the drawings.

The plate 44 is provided with an upward extension 45 which has a curved recess 46 to engage a pin or projection 47 carried by the upper prong 31 of the latch or locking bolt and extended forwardly from said prong, and said plate is provided with an opening 48 to receive the front portion of 75 the sleeve 22, which sleeve is provided with diametrically disposed recesses 49 which extend from its front end to near the middle of the sleeve as is clearly shown in Figs. 2 and 3 of the drawings. These recesses are 80 adapted to register with recesses 50 arranged diametrically with respect to the opening 48 in the plate 44 and are employed for the purpose of engaging projections 51 which are diametrically disposed on 85 the knob spindle 28, under certain movements or conditions of said spindle. It will be observed by reference to Fig. 2 that the slot 43 in the plate 44 is diagonally disposed in a lateral extension 52 of said plate and 90 that said slot is of slight cam formation.

Mounted between the studs 36 and between the arm 30 and plate 44 are a number of elements of the lock which will now be described. On the front surface of the member 30 a thin metal washer 53 surrounding the sleeve 22 is mounted in engagement with the studs 36 so as to prevent it turning, and this washer has a recess 54 in its periphery registering with the recess 100 35 in the disk portion 33 of the arm 30 but of smaller dimensions or rather of less width than the last named recess. Mounted on the front surface of the washer 53 and rotatably surrounding the sleeve 22 is a 105 disk tumbler 55 which has a recess 56 in its periphery to register with the recess 54 of said washer.

Located on the front surface of the tumbler 55 is a spacing ring 60 which is of 110 larger diameter than said tumbler and engages at its periphery the studs 36 between which it is located to prevent its rotary movement. The ring 60 is of a broken type 115 and has its ends spaced to form a recess 61 to register with the recesses 56, 54 and 35 of the just above named element.

Mounted on the front surface of the ring 60 so as to turn on the sleeve 22 is another tumbler 62 which has a recess 63 in its periphery to register with the recess 61 of the ring 60. Mounted on the front surface of the tumbler 62 is a spacing ring 64 of the same size and construction as the ring 60 and mounted in a like manner. The recess 65 of the ring 64 is adapted to register with the previously named recesses. Mounted on the front surface of the ring 64 is the front or outermost tumbler 66 which is adapted for rotary movement on 130

the sleeve 22 and has in its periphery a recess 67 adapted for registration with the other recesses. This tumbler 66 has a centrally disposed key-way 67^a for the projections 51 on the spindle 20. The rear tumbler 55 is provided on its front surface with a projection such as a small screw 68 and the intermediate tumbler 62 is provided on each of its side surfaces with a similar projection 68 while the front tumbler is provided on its rear surface with a similar projection to engage the projection 68 on the front surface of the intermediate tumbler. These projections are arranged so that they will travel in the same circle so that when it is desired to set the combination of the lock they will impinge one another when the tumblers are turned in the proper directions.

Between the front tumbler 66 and the plate 44 is interposed a thin metal washer 69 of the same construction as the washer 53 and mounted in the same way. As will be seen in Figs. 3 and 5, the front knob 21 has its extreme rear portion reduced and provided with an annular flange 70 at its rear end, and that this reduced portion is located in the cavity of the head 27 of the rear knob spindle 28. To afford a swivel connection between the spindles 20 and 27 the head 28 of the last named spindle is provided with a screw-threaded opening 71 for the reception of a screw 72 which is extended through the cavity of the head 27 so as to permit locking movement of either of the spindles and also so as to restrict the longitudinal movement of the front spindle 20, for it is apparent that the flange 70 on the rear end of said spindle will restrict its forward movement.

It will be seen that the spindle 20 is cylindrically enlarged as at 73, which enlarged portion rests at its inner end when the parts of the lock are in the positions shown in the various views of the drawings, so as to permit retraction of the latch or bolt, on the front surface of the front plate 18 of the lock casing, it being understood that said cylindrically enlarged portion is extended through an enlarged opening in the front surface of the door.

Outwardly of the enlarged part 73 the spindle 20 is reduced as at 74, see Fig. 5, and has detachably secured on said reduced portion by means of a screw 75, the front knob 21, which screw is extended through a suitable opening in a portion of said knob and is seated or engages the reduced portion 74 of the said spindle. Between the portion of the knob 21 which surrounds the reduced portion 74 and the outer end of the enlargement 73 is mounted for rotation a milled disk 76 which has in its surface adjacent the enlargement 73 a pair of diametrically disposed concaved recesses 77 and 78 for co-operation with the outer end of a spring-actuated bolt 79, which bolt as well as its spring, is located in a longitudinally disposed opening 80 near the periphery of the enlarged part 73 as is clearly shown in Fig. 5 of the drawings, in which view it will be observed that the recess 77 in which the outer head of the bolt 79 is located, is deeper than the recess 78 and that when the parts of the lock are in the positions shown in the various views of the drawings, the inner end of the bolt 79 will rest against the outer surface of the front plate 18 of the lock casing.

The cylindrical part 73 is provided with a longitudinally disposed key seat 81 for co-operation with a key or projection 82 with which the dial plate 83 is provided at the edge of its central opening through which the enlargement 73 of the spindle 20 is extended. The dial plate 83 is protected by a centrally orificed housing 84 which is mounted on and secured to the front face of the door by means of screws or otherwise, and said housing carries an apertured glass plate 85 near its front portion through which the graduated scale of the dial plate may be seen. The front face of the housing 84 is provided with an index 86, see Fig. 1, to be used when the dial is turned for setting the combination of the lock in the well known way.

From the foregoing and by reference to the drawings, it will be readily understood and clearly seen that when the parts are arranged as shown in Figs. 2 to 5 inclusive, the bolt or latch 13 may be operated as a latch from either side of the door by turning the knob 21 or the knob 29 in the proper direction, for it is apparent that as the plunger 40 engaging through its projection 42 and slot 43 the extension 52 of the plate 44, will occupy about the position shown by dotted lines in Fig. 2 or so that its reduced portion 41 will not be in engagement with the recesses of the tumblers but in proper position to be forced into such engagement by turning the plate 44 by means of the knob 21 and its spindle to the right. In this operation the projections 51 on the spindle 20 will engage the recesses 50 in the plate 44 thus permitting it to be turned so that the bearing or recess 46 in the extension 45 of said plate will co-operate with the projection 47 on one of the prongs 31 of the latch to retract the same.

In order to prevent the tumblers being accidentally turned by the inward and rotary movement of the spindle 20 and its projections 51, the turning member or disk 76 may be turned from the position it occupies as shown in Fig. 5 to such position that the shallow recess will receive the rounded end of the spring pressed bolt 79, it being understood that by turning the member 76 the

bolt 79 will be forced inwardly from the recess 77 so that its outer end will ride on the inner face of the member 76 until it reaches the shallow recess 78, in which it will be seated, thus causing its inner end acting against the outer surface of the front wall 18 of the casing to force the entire spindle 20 outwardly so that the parts will assume about the positions shown by dotted lines in Fig. 3, in which positions the projections 51 on the spindle 20 will be held in engagement with the recesses 50 of the plate 44 and free from engagement with the front or outermost tumbler. It is apparent that the screw or member 72 co-acting with the flange 70 on the inner end of the spindle 20 will restrict the outward movement of said spindle. It will be understood that the bolt 13 can be operated as a latch at all times by means of the knob 29 and its connections with the arm 30 by simply turning the knob 29 in the proper direction to actuate said arm against the prong 31 in a direction against the tension of the springs 38 which serve to hold the latch 13 in its normal position.

In order to set the tumblers in combination without removing the lock from the door, should the combination be accidentally disarranged, for instance, by one not familiar with the operation of the lock, the rear plate 16 of the casing is provided between the opening 19 therein for the spindle 20 and sleeve 22 and the outer side wall of the casing at a point over the inner end of the tongue or reduced portion 41 of the plunger 40 and over the peripheries of the tumblers, with an opening 19^a, see Fig. 6, which registers with an opening 87 in the rear surface of the door at a point between the rear spindle 28 and the free edge of the door, as shown in Fig. 4 of the drawings. By this arrangement it is manifest that by removing the knob 29 the plate 88 used for ornament and secured to the door can be removed so that the manipulation of the tumblers caused by the rotary movement of the spindle 20 can be seen through the registering openings 87 and 19^a to the end that the combination can be easily effected.

Having thus fully described my invention, what I claim as new and desire to secure by Letters Patent is:—

1. A lock of the class described including in combination with a casing, a spring actuated latch or locking bolt having a projection on one of its surfaces and a guide-way, a sleeve having diametrically disposed recesses extended therein from one of its ends and mounted for rotary movement in the casing, a plate rotatably mounted on the sleeve at the recessed end thereof and having diametrically disposed recesses communicating with those of the sleeve, said plate having an extension provided with a slot dia-

nally disposed with respect to said sleeve and also having another extension provided with a recess to engage the said projection on the said bolt, a rotary reciprocating knob spindle mounted transversely in the casing 70 and extended into said sleeve, lateral projections carried by the spindle and extended through the recesses of the sleeve and adapted for engagement with the recesses of said plate, and a plunger slidably mounted in the 75 guide-way of said bolt and having a projection engaging the slot of the extension of said plate.

2. A lock of the class described including in combination with a casing, a spring-actuated latch or locking bolt having a pair of spaced prongs and between the same a guide-way, a projection on one of said prongs, a sleeve having at least one recess extended therein from one of its ends and transversely mounted in the casing for rotary movement, a plate rotatably mounted on the sleeve at the recessed end thereof and having at least one recess communicating with the recess of the sleeve, said plate having an extension provided with a slot diagonally disposed with respect to said sleeve and also having another extension provided with a recess to engage the said projection on one of the prongs of the bolt, a rotary knob 95 spindle mounted transversely in the casing and extended into said sleeve, a projection carried by the spindle and extended through the recess of the sleeve and in engagement with the recess of said plate, and a plunger slidably mounted in the guide-way of said bolt and having a projection engaging the slot of the extension of said plate.

3. In a lock of the class described, the combination with a casing, of a spring actuated latch or locking bolt therein, a sleeve having a recess extended therein from one of its ends and transversely mounted in the casing for rotary movement, a series of tumblers mounted for rotation on the sleeve and each having a recess in its periphery and provided with means for inter-engagement with one another for setting the combination thereof, the outermost tumbler having at least one recess leading from its central opening, a rotary reciprocating knob spindle mounted transversely in the casing and extended into said sleeve, at least one lateral projection carried by the spindle and extended into the recess of the sleeve and adapted for engagement with the recess of the outermost tumbler, a plate rotatably mounted on the sleeve and having a recess communicating with the recess of the sleeve and adapted for the passage therethrough or the engagement therewith of the projection on the spindle, said plate having an extension provided with a slot diagonally disposed with respect to the sleeve and also an extension provided with a recess, a pro-

- jection on the latch or locking bolt engaging said recess, and a plunger slidably mounted and guided by the latch and provided with a reduced portion to enter and engage the recesses of said tumblers, said plunger having a projection extended into the slot of said plate.
4. In a lock of the class described, the combination with a casing, of a spring-actuated latch or locking bolt therein, a sleeve having diametrically disposed recesses extended therein from one of its ends and transversely mounted in the casing for rotary movement, a series of tumblers mounted for rotation on the sleeve and each having a recess in its periphery and provided with means for inter-engagement with one another for setting the combination thereof, a rotary reciprocating knob spindle mounted transversely in the casing and extended into said sleeve, lateral projections carried by the spindle and extended through the recesses of the sleeve, a plate rotatably mounted on the sleeve and having diametrically disposed recesses communicating with those of the latter and adapted to receive said projections on the spindle, said plate having an extension provided with a diagonally disposed slot and also an extension provided with a recess, a projection on the latch or locking bolt engaging said recess, a plunger slidably mounted and guided by the latch and provided with a reduced portion to enter and engage the recesses of said tumblers, said plunger having a projection extended into the slot of said plate, an arm rotatably mounted on the end of the sleeve opposite its recess and pivotally connected at its other end to said latch or locking bolt, said arm having a pair of openings diametrically disposed with respect to said sleeve, and a rear knob spindle swivelled and slidably connected to the inner end of the first named spindle and carrying a pair of spaced projections for engagement with said openings in said arm.
5. In a lock of the class described, the combination with a casing, of a spring-
